[57] CLAIM

The ornamental design for a model racing car, as shown and described.

DESCRIPTION

FIG. 1 is a front perspective view of a model racing car showing my new design;

FIG. 2 is a left side perspective view thereof, the side opposite being substantially a mirror image;

FIG. 3 is another front perspective view thereof shown on an enlarged scale; and,

FIG. 4 is a rear perspective view thereof.

Fig. 1.

Fig. 2.

Fig.3.Fig.4.
